UNITARY FAN BLADE STRUCTURE

Arthur E. Kline and Wendell H. Webster, Albion, Mich.,
assignors to Lonergan Manufacturing Company, Albion,
Mich., a corporation of Michigan

Application April 6, 1953, Serial No. 24,362

Term of patent 14 years

(Cl. D26—7)

To all whom it may concern:

Be it known that we, Arthur E. Kline and Wendell H. Webster, citizens of the United States, and residents of Albion, in the county of Calhoun and State of Michigan, have invented a new, original, and ornamental Design for a Unitary Fan Blade Structure, of which the following is a specification, reference being had to the accompanying drawing forming a part thereof.

Figure 1 is a perspective view of one face of the unitary fan blade structure embodying the design; and

Fig. 2 is a perspective view of the other face of the unitary fan blade structure embodying the design.

We claim:

The ornamental design for a unitary fan blade structure, substantially as shown.
